ABSTRACT OF THE DISCLOSURE

A lamp gettering method and apparatus which provides a series of constant current pulses of predetermined duration and magnitude through a filament sufficient to flash getter material from the filament but insufficient to cause the filament to recrystallize and thus become brittle. The IR drop across the filament is sensed, compared to a maximum permissible value and the duration of the constant current pulses controlled to maintain the IR drop across the filament and hence the getter flashing temperature at a predetermined level.

The present invention relates to lamps and, more particularly, to an electronic flashing control apparatus and method having particular application to the flashing of an electric lamp to activate the customary getter by heating the filament to a uniform temperature.

In order to "getter" electric lamps it is necessary to "flash" the lamp by heating the filament to a temperature sufficient to activate the getter. When so activated, the getter then combines with the residual impurities remaining in the lamp after it has been evacuated. Heretofore no satisfactory and dependable way has been known to maintain the lamp filament at a uniform predetermined temperature during gettering with the result that too frequently the filament temperature was raised to the recrystallization point resulting in fragile and saggy filaments. By the flashing control system of the present invention, the flashing of the getter is accomplished in less time than heretofore, by maintaining the temperature of the filament uniform during flashing. This is achieved by subjecting such filament to a constant preselected current as a function of desired temperature thus eliminating the possibility of filament recrystallization with ensuing fragility and sagging.

The problem of getter flashing has been particularly severe with miniature-type, evacuated lamps since a relatively large amount of getter must be completely flashed from the very fine filament during the lamp fabrication. In the case of Christmas tree lamps, the fabricated lamp must be coated with a color filter, and the shocks encountered during coating have resulted in an undue amount of product "shrinkage" because of the brittle, recrystallized filaments. In the past, such lamps have usually been hand packed because of the brittle filaments and a large amount of customer breakage has resulted when these lamps were sold loose from bins or store counters.

It is accordingly the primary object of the present invention to provide an improved method and apparatus for flashing the getter during fabrication of an electric lamp and which consistently produces stronger filaments than heretofore.

Another object of the present invention is the provision of an electronic flashing control system which applies constant current to the lamp filament throughout each flash.

A further object of the present invention is the provision of an electronic flashing control system for the

2

flashing of a getter in an electric lamp during its fabrication wherein the duration of the arc in each flash is controlled.

An additional object is to provide an incandescent, evacuated lamp, preferably of the miniature type, which can be handled readily either in the factory or by the customer, without breaking the filament.

The foregoing objects of the present invention, together with other objects which will become apparent to those skilled in the art from the following description, are achieved by providing a flashing control method and apparatus which senses the character of current flow through the lamp during gettering and distinguishes between gaseous and metallic conduction. Thereupon the gaseous conduction is kept within safe time limits and the metallic conduction within safe but effective voltage limits, which voltage limits together indicate the maximum instantaneous temperature limits that a filament may reach during flashing, under utilization of constant current control as a measure thereof. There is also provided the resulting product.

The present invention can be more readily understood by reference to the accompanying drawings wherein:

FIGURE 1 is a block diagram illustrating various parts of the electronic flashing control of the present invention and showing the shape of the wave as produced by such circuit part,

FIGURE 2 is a diagram of the circuitry of the electronic flashing control system, and

FIGURE 3 is a graphic illustration of the shape of the current, voltage and temperature waves as produced by the electronic flashing circuit as shown in FIG. 2.

The following constitutes a brief outline of the operation of the present system. The incandescent filament which is being flashed is formed of tungsten and displays an electrical resistance which increases sharply with increasing temperature. When a constant current of given magnitude is passed through a cold tungsten filament, the resulting IR drop across the filament will be relatively small, since the filament electrical resistance is low. When the same constant current is passed through a hot filament, however, the resulting IR drop across the filament will be relatively large, since the filament resistance is now correspondingly high. The apparatus comprises a current supply means for passing through the filament a series of constant current pulses of predetermined duration and magnitude. These pulses rapidly heat the filament to a predetermined temperature sufficient to flash getter material from the filament, but which temperature is insufficient to cause the filament to recrystallize and thus become brittle. This constant current supply means comprises the "trigger pulse generator" 5, the "ON" square wave generator 7, the "OR" gate 9, and the "current regulator" 12, as shown in block diagram in FIG. 1.

There is also provided a voltage detecting and signalling means which responds to the IR drop developed across the lamp filament when the constant current pulses are passed therethrough. The voltage detecting and signalling means acts to generate a control signal when the IR drop developed across the heated filament reaches a predetermined value which signifies that the filament getter flashing temperature has been achieved. The voltage detecting and signalling means comprises the "cut-off voltage reference or voltage leveler" 17 and the "voltage comparator" 15, as shown in FIG. 1.

A current pulse control means responds to the control signal generated by the above-noted voltage detecting and signalling means to shorten the duration of each constant current pulse passed through the lamp filament by the above-noted current supply means. This decreases the

average wattage consumed by the filament by such amount that the resulting IR drop across the filaments during each such shortened constant current pulse, is maintained substantially at that predetermined value which indicates that the predetermined filament getter flashing temperature has been achieved. The current pulse control means comprises the "OFF" square wave generator 10 working through the "OR" gate 9 to limit the duration of each constant current pulse supplied to the lamp filament by the "current regulator," as shown in FIG. 1.

Finally, a timing means comprising the switch 24 and associated cam, as shown in FIG. 2, operates to control the above-noted current supply means to pass constant current pulses through the lamp filament for a predetermined time which is sufficient to completely flash the getter material from the lamp filament.

Referring now to the drawings in detail the "trigger pulse generator" 5 of FIG. 1 comprises a standard multivibrator circuit with its time constants adjusted to give a desired trigger pulse repetition rate of 500 pulses per second for a period of 1.6 seconds which are supplied to the electric lamp during its approximately 2.4 seconds dwell at the "getter flashing" station, although such pulse repetition rate and duration period as supplied are not critical and can be varied. When the machine indexes a lamp to its getter flashing position, a switch is opened to cause the wave form 6 thus generated, and as shown in FIG. 1, to be thereafter transmitted to an "ON" square wave generator 7 which is operable to emit a signal pulse of predetermined length. The length of this pulse is determined by a simple adjustment of the time constants of this "ON" square wave generator, which latter comprises a standard one-shot multivibrator circuit producing a square wave form 8, as shown in FIG. 1, with this signal pulse feeding one side of an "OR" gate 9.

The "OR" gate 9 opens only when the "ON" pulse is present on one side as controlled by a timing circuit and an "OFF" square wave generator 10 has not signalled the other side of the "OR" gate. Also the "OFF" square wave generator 10 can close the "OR" gate 9 at any time, even while on "ON" pulse is still present on the other side of the "OR" gate. When the "OR" gate 9 is open and conducting, a pulse 8 from the "ON" square wave generator 7 passes through the "OR" gate 9 and signals a current regulator 12 to pass a rectangular pulse 13 of constant amplitude onto the lamp 14. This current regulator 12 is a feedback amplifier circuit which allows the voltage across the lamp 14 to build up as its resistance increases, so that the voltage can increase from an initial twenty-five volts to over four hundred volts without detrimentally effecting the operation of the current regulator 12 to maintain the current through the lamp 14 at a desired constant level.

The voltage comparator 15 senses the instant that the voltage across the lamp 14 exceeds the cut-off level which as hereinafter described in detail is set at three hundred volts. At this 300 volts cut-off level, the voltage comparator 15 triggers the "OFF" square wave generator which sends a negative pulse 16 to the "OR" gate to close the latter and terminate that pulse, with the "OFF" pulse lasting until after the "ON" pulse has been completed. Before the next "ON" pulse arrives to the "OR" gate 9, the negative "OFF" pulse ends and unlocks the "OR" gate so that it is opened by the next "ON" pulse.

Since the "ON" pulses last for 0.44 milliseconds, as shown by the "Current" wave form in FIG. 3, and the current pulses as previously mentioned are supplied to the lamp 14 at a rate of 500 pulses per second, the heating effect of these pulses on the lamp 14 is cumulative. Each pulse accordingly imparts more heat to the filament than is lost by the filament during the 1.56 millisecond interval between pulses with the result that each such pulse raises the filament of the lamp 14 to a still higher temperature as shown by the "Temperature" curve in FIG. 3. Inasmuch as the current through the filament of lamp 14 is held

constant by the current regulator 12, as also shown by the "Current" curve in FIG. 3, such temperature rise to a maximum of about 2100° C. (FIG. 3) is accompanied by a corresponding increase in its resistance. This results 5 also in a rise in the voltage across such heated filament, as shown by the "Voltage" curve of FIG. 3, in accordance with Ohm's law from about 25 volts at room temperature to a cut-off voltage across the lamp of 300 volts, as set by the Cut-Off Voltage Leveler 17 (FIG. 1).

Because the filament of the lamp 14 cools very little 10 during the 1.56 milliseconds interval between pulses, the succeeding pulses of 0.44 milliseconds duration will bring the filament of the lamp 14 up to the voltage cut-off of 300 volts in less than one second, as can be seen from both 15 the "Temperature" and "Voltage" curves of FIG. 3. Once this desired temperature and its corresponding voltage cut-off is reached the length of each pulse in the train is automatically shortened, as seen by the "Current" curve of FIG. 3. Thereafter the succeeding pulses will bring 20 the temperature and hence the voltage to its cut-off value of 300 volts in less than one tenth of a millisecond with the remaining three or four tenths of a millisecond of the "ON" pulse being suppressed by the "OFF" pulse.

By reference now more specifically to the circuit diagram of FIG. 2 it will be noted that the lamp 14 when at its "gettering" position of the lamp making machine is adapted to receive energy from the "Current Regulator" 12. This regulator 12 comprises a "700 Volt Supply" 25 for energizing the lamp 14 through a current regulator 30 and feedback amplifier tube V4 with the screen grid of such tube receiving a biasing potential from a "280 Volt Screen Grid Supply" under control of a tube V5. A variable resistor R43 is included in the energizing circuit for the lamp 14 and has one of its ends connected 35 by a conductor 22 to the negative side L2 of a "450 Volt Supply" source while the control grid of current regulator tube V4 is likewise connected by a conductor 23 to the plate electrodes of a constant current regulator tube V6 and through a resistor R21 to the cathode of a control 40 tube V2 and one end of a further resistor R22, all of which form part of the previously mentioned "OR" gate 9, and thence from the other end of resistor R22 to the negative conductor L2.

During indexing movement of the lamp making machine, and hence from the time a "gettered" lamp 14 is moved out of its station and a new lamp 14 is moved into the "gettering" station, the signal from the conventional trigger pulse generator 5 (not shown) is rendered ineffective by closure of a cam-operated switch 24 which connects the supply conductors 25 and 26 from such generator together, with a resistor R56 thereupon constituting the sole pulse generator load. At this particular moment the various elements of the circuit of FIG. 2 will be in a definite relationship. For example, control tube V5 will 45 be conducting and hence a potential is supplied to the screen grid of current regulator and feedback amplifier tube V4, but due to the potential on the control grid of this tube it is non-conducting. The "ON" square wave generator tube V1 is actually a dual tube, as are the remaining tubes in FIG. 2, and hereinafter the left-hand 50 section of each such tube will be identified by the letter "A" and the right-hand section by the letter "B." At the same time multivibrator "ON" tube V1B is conducting 55 since its grid receives an appropriate potential relative to its cathode from a capacitor C1 which has been previously charged through a resistor R4. Thus current flows from the positive side L1 of the "450 Volt Supply" through a resistor R5 and tube section V1B to a common resistor R20 and back to negative supply conductor L2. 60 Due to the cathodes of both tube sections being tied together, the same potential is imposed thereon and since this potential is higher than that supplied to the grid of section V1A, this section is then non-conducting.

At the same time that section of tube V1B is conducting 65 the section V2A of the cathode follower tube V2 of

the "OR" gate 9 is likewise conducting. This is due to the fact that since there is conduction through R5 with a voltage drop thereacross, a lower potential is impressed on the cathode of a crystal diode CR2 than on its anode which is connected to the supply conductor L1 through a resistor R7 and hence diode CR2 becomes conductive. This causes the flow of current through diode CR2 with a voltage drop across resistor R7 and since the latter is connected to the grid of tube section V2A the potential impressed thereon is lowered. Also, since this tube section is initially conducting with current flow from positive conductor L1 through tube section V2A and previously mentioned resistor R22 to the negative supply conductor L2, the flow of current through this resistor R22 is greatly reduced by lowering of the potential on the grid of tube section V2A. This tube V2A being a cathode follower with the load resistor R22 on the cathode side instead of its anode side results in the tube automatically adjusting itself so that its cathode always remains just a few volts above the potential impressed on its grid. Since the cathode of section V2A, as previously mentioned, is connected through resistor R21 and conductor 23 to the grid of current regulator and feedback amplifier tube V4, whatever potential the cathode of V2A assumes at any given moment, there will be a constant difference between that potential and the voltage supplied to the grid of current regulator and feedback amplifier tube V4.

Still during this period that cam-operated switch 24 is closed and the trigger pulse generator 5 is inoperative, the constant current regulator tube V6 of the "OR" gate 9 is conducting inasmuch as tube section V2A, as previously mentioned, is now conducting and consequently current flows from line conductor L1 to tube section V2A (by-passing resistor R7) and thence through parallel resistor R21 to the plates of regulator tube V6. Such current then flows from the cathodes of tube V6 through common resistor R45 and a pair of resistors R51 and R53, through the negative conductor B2 from a "450 Volt Bias Supply" and thence through such bias supply to its positive conductor B1 which also constitutes a negative conductor L2 for the "450 Volt Supply." The voltage on the cathodes of regulator tube V6 relative to its grid voltages controls the flow of current therethrough so that this current is constant. This constant current through constant resistor R21 thereby produces a constant voltage drop thereacross so that any voltage change on the cathode of "OR" gate tube V2A is faithfully reproduced at the lower end of resistor R21 but at a lower D.C. voltage level. This latter voltage is then supplied by the conductor 23 to current regulator and feedback amplifier tube V4 as its grid bias and until the decreased flow of current through resistor R7 imposes a higher voltage on the grid of tube section V2A and on its cathode, the additional drop through resistor R21 causes the grid of tube V4 to render such tube non-conducting and hence no current flows from the "700 Volt Supply" to the lamp 14.

It will be noted from FIG. 2 that the grids of the constant current "OR" regulator tube V6 are supplied with a potential from the "450 Volt Bias Supply" through a potentiometer R32 and fixed resistors R51 and R53. A capacitor C6 is connected across this bias supply source through resistor R51 and similarly a pair of series connected voltage regulator tubes V8 and V9 are connected through the resistors R53 and R51 to this bias supply source. The purpose of such resistors R51 and R53 together with tubes V8 and V9 is to maintain a fixed voltage of 300 volts across such tubes V8 and V9 and it is a portion of the voltage from this constant source that is impressed upon the grids of the constant current regulator tube V6 as selected by the potentiometer R32. At the moment that current regulator and feedback amplifier tube V4 is non-conducting there is of course no current flow through lamp 14 and hence no voltage drop thereacross. However, such lamp is connected by con-

ductor 22 to the negative side L2 of the "450 Volt Supply" and hence is at ground potential while the other side of the lamp 14 is likewise at ground potential being connected to the negative side of the "700 Volt Supply" and to the cathode of a crystal diode CR4. The anode of this diode CR4, however, is supplied with a negative potential as set by a potentiometer R36 of the "Cut-Off Voltage Leveler" 17, which derives its voltage from conductor L2 also common with positive bias conductor B1, and from negative bias conductor B2 through a resistor R55 and a conductor 29, so that when the lamp 14 is unenergized this crystal diode CR4 is non-conducting. A capacitor C15 bridges this potentiometer and hence is connected to diode CR4 as its load.

Prior to arrival of a pulse from trigger generator 5, the multivibrator tube section V3A of the "Off Square Wave Generator" 10 is conducting since the grid thereof is supplied with a high potential from a capacitor C17 which has been previously charged through a potentiometer R12. A small grid current accordingly flows to the cathode and through a common cathode resistor R24 to negative conductor B2 and thence through resistors R53 and R51, then the "450 Volt Bias Supply" to the positive bias conductor B1, and constituting also negative conductor L2, and through the "450 Volt Supply" back to conductor L1 thus completing the grid current circuit of tube section V3A. Simultaneously with this small grid current flow there will also be plate-cathode conduction with current flow from supply conductor L1 through resistor R10 to the plate of tube section V3A and from the cathode thereof through the same remaining portion of the above mentioned grid current circuit. Tube section V3B of the "Off Square Wave Generator" 10 is rendered non-conducting at this time by virtue of the voltage impressed upon the grid from potentiometer R17 which is set at a lower voltage than that developed at the cathodes of tube V3 by the current flowing through resistor R24 during conductivity of tube section V3A and since tube section V3B is thus non-conducting no current then flows through the plate resistor R44.

At the same time that tube section V3A is conducting there is a path of current flow from supply conductor L1 through a resistor R14 and potentiometer R17 to the lower end of common cathode resistor R24 and by conductor B2 through the remainder of the grid and plate circuits of tube section V3A just above mentioned. Current also flows from the adjusted setting of potentiometer R17 through a resistor R39 in electrical parallel with a crystal diode CR5 which charges a capacitor C7 and then passes through section V7B of a dual triode tube and constituting the "Voltage Comparator" 15. From such tube the current then flows to a common cathode resistor R41 and thence by the aforesaid conductor 29 and resistor R55, the negative bias conductor B2, then through the "450 Volt Bias Supply" and positive bias conductor B1 which is also negative supply conductor L2, thus completing the circuit through "Voltage Comparator" tube section V7B which is now conductive at this time. A current path is also simultaneously established directly to the plate of tube section V7B from positive supply conductor L1 through a resistor R15. Tube section V7A of "Voltage Cut-Off Leveler" 17 is likewise conducting at this time since the voltage impressed on its grid by potentiometer R36 is above the voltage at the lower end of cathode resistor R41. The plate of tube section V7A is connected directly to the positive bias supply conductor B1 while its cathode is connected through common cathode resistor R41, conductor 29 and resistor R55 to the negative bias supply conductor B2. Thus tube section V7A of the "Cut-Off Voltage Leveler" 17 is supplied entirely from the 450 Volt Bias Supply: while its other section V7B is supplied from both the "450 Volt Bias Supply" and the "450 Volt Supply" with their cathodes being common to each other.

and set at the same potential by adjustment of potentiometer R36.

Assuming now that the machine has indexed a lamp 14 into its "gettering" station, the cam-operated switch 24 will then open during the 1.6 seconds rotation of the high surface of such cam switch when the lamp 14 is of the "gettering" station, as shown in FIG. 2. At this time the trigger pulse generator 5 producing its aforementioned 500 pulses per second is rendered operative with a current pulse flowing by way of conductors 25 and 26 as well as resistor R56 to develop a voltage across a resistor R57. The voltage thus developed across resistor R57 is a negative pulse and hence crystal diode CR1 is rendered conductive thus lowering the potential on the plate of tube section V1A from that previously supplied from positive supply-conductor L1. The coupling of capacitor C1 to the plate of V1A lowers the potential on the grid of tube section V1B which decreases the flow of current through this tube section V1B and the common cathode resistor R20 which thus lowers the potential on both the cathodes of tube sections V1A and V1B.

This lowering of the potential on the cathode of "ON" tube section V1A tends to make the potential impressed on its grid appear to go positive relative to the cathode thereby causing this section V1A to become conductive and causing a voltage drop to occur through plate load resistor R3 with attendant lowering of the plate potential. This lower potential is again transmitted to the grid of "ON" tube section V1B by capacitor C1 but greatly amplified by the action of section V1A, so that this still lowered potential on the grid causes the cathode of section V1B to descend even further carrying with it the potential on the cathode of tube section V1A and resulting in the latter becoming even more vigorously conductive until it becomes saturated whereby tube section V1B is then cut-off, i.e. becomes non-conductive. When the latter tube section V1B is completely cut-off there is no longer any current flow through resistor R5 and hence the potential on the plate of this tube section V1B rises to the 450 volts of supply conductor L1. This increased potential causes the flow of current through "OR" gate resistor R7 to cease because both sides of the crystal diode CR2 are now at very nearly the same potential.

However, this cessation of current flow through resistor R7 causes a great rise in the potential then impressed on the grid of "OR" tube section V2A which being a cathode follower raises the voltage of the cathode due to the increased current flow through resistor R22. The grid of current regulator and feedback amplifier tube V4 is raised the same number of volts as that of the cathode of the cathode-follower tube V2A with the difference in voltage from the beginning to the top of the pulse being practically the same in each case except that the constant voltage drop across resistor R21 by the action of tube V6 causes the grid of the regulator tube V4 to start from its low negative cut-off voltage when the pulse comes through the cathode follower tube V2A and rise to a sufficiently high voltage to cause the current regulator and feedback amplifier tube V4 to become conductive. Upon tube V4 becoming conductive a current flows from the "700 Volt Supply" causing a voltage to develop across cathode resistor R43. Since the lower end of resistor R43 is connected by conductor 22 to negative supply conductor L2, and the grid of tube V4 is likewise connected to this same supply conductor L2 by means of conductor 23 and resistors R21 and R22, this flow of current through R43 causes the cathode of tube V4 to rise in voltage above that of its grid. This tends to reduce and thereby stabilize the current at a level as determined by the magnitude of the voltage impressed on the grid of tube V4.

The current of about 0.15 amperes flowing through the current regulator and feedback amplifier tube V4 to the lamp 14 during each pulse is maintained constant by the circuits connected to the resistor R43 which determine the voltage developed thereacross, with the height of current

amplitude of the pulse controlled by setting of such resistor R43. At this point following initiation of the pulse from the trigger pulse generator 5, the only tubes that have changed their operating status from the "pre-pulse" state are "ON" tube section V1A and tube V4 of "Current Regulator" 12 which have altered from non-conducting to conducting. The initial pulses supplied to the lamp 14 from the "700 Volt Supply" under control of the tube V4, break into arc discharges but are so few in number and of such extremely short duration as to not be detrimental. The current thereafter passes through the filament, in the manner shown by the "VOLTAGE" curve of FIG. 3. These initial pulses are insufficient to develop the desired 300 volts across the lamp 14 being getter flashed and so such pulses continue for intermittent periods of 0.44 milliseconds duration as shown by the "CURRENT" curve of FIG. 3. Such period is determined by the resistor R4 and a capacitor C1 together with the setting of a potentiometer R16 for tube V1 and lasts for 0.44 milliseconds unless 300 volts is developed across the lamp filaments, at which time the latter will have reached its maximum temperature of 2100° C. so that thereafter the pulse periods decrease to less than 0.44 milliseconds, all as seen in the curves of FIG. 3.

Inasmuch as the pulse started, as previously mentioned, when a negative potential was impressed by capacitor C1 on the grid of "ON" tube section V1B, the pulse lasts during recharging of this capacitor C1 through resistor R4 until the potential on the grid thereof reaches a value sufficient to cause tube section V1B to again start to conduct. As this occurs the cathode of section V1B begins to rise in voltage, because of the increased current flowing through resistor R20, and such rise in voltage is also impressed on the cathode of "ON" tube section V1A which tends to cut-off this latter section. As less current therefore flows through section V1A, less current flows through resistor R3 which supplies such tube section, thereby causing the potential on the plate of section V1A to rise. Since this rise in potential is coupled by the capacitor C1 to the grid of tube section V1B, this causes such section to conduct even more vigorously with increased current flow through resistor R5 and tube section V1B. This increased current flow through this resistor R5 lowers the plate potential as tube section V1B again becomes fully conductive. Such conduction of section V1B increases the current through cathode resistor R20 which raises the cathode voltage above that impressed on the grid as set by the potentiometer R16 thereby rendering tube section V1A non-conductive and terminating the "ON" pulse.

Assume that the voltage across the filament of lamp 14 has now reached the 300 volts, as was set by the cut-off adjustment of potentiometer R36. This voltage is reached when the preset controlled current pulses have raised the filament temperature to approximately 2100° C. and thus increased the hot resistance to the point of developing 300 volts when the constant current pulse flows therethrough and it is desired to maintain this 2100° C. temperature to the end of the 1.6 second getter flashing period. While "ON" tube section V1A is conducting, the current regulator and feedback amplifier tube V4 will likewise be conducting with a constant flow of current from the "700 Volt Supply" heating the filament of lamp 14 and hence increasing its resistance. This constant current flows through the filament with increased resistance causes an increase in the voltage thereacross as the temperature of the filament rises, and such voltage increase lowers the voltage on the negative side of the "700 Volt Supply" relative to that on the common conductor B1-L2 since current regulator and feedback amplifier tube V4 is part of that feedback arrangement. Accordingly, when the voltage on the negative side of the "700 Volt Supply" drops below the voltage set by the "Cut-off Voltage Leveler" potentiometer R36, the capacitor C15 rapidly discharges through crystal diode CR4 which voltage drop

is "Sensed" by "Voltage Comparator" tube section V7B and its grid then becomes negative with respect to the cathode thereof.

However, the grid of "Cut-off Voltage Leveler" tube section V7A is de-coupled by resistor R40 from crystal diode CR4 and is maintained at its original voltage by the charge on capacitor C16 and the isolation provided temporarily by resistor R40. Hence there is conduction from the common conductor B1-L2 to the plate of tube section V7A and through such tube to the resistor R41 which holds the cathodes of both tube sections V7A and V7B at a relatively fixed potential. The grid of tube section V7B being carried downward in voltage cuts off conduction through this tube section with an attendant rise of the voltage on its plate due to a decrease in current flow through plate-supply resistor R15. This voltage rise is accordingly conducted as a positive pulse through capacitor C7 to the grid of "OFF" tube section V3B which had been previously rendered non-conducting by the previously described multivibrator action. Although section V3B had initially been non-conducting because the potential of its grid was below that impressed upon its cathode, the positive pulse now supplied to the grid by capacitor C7 renders such "OFF" tube section V3B conductive, with the same ensuing regenerative action as was hereinbefore described relative to "ON" generator multivibrator tube V1, to cut-off tube section V3A.

When "OFF Square Wave Generator" tube section V3A is thus rendered non-conducting the reduced current flow through resistor R10 causes the voltage to rapidly rise on the plate of section V3A and being a positive pulse is impressed through the capacitor C2 and a resistor R9 upon the grid of "OR" gate tube section V2B thereby rendering such section conductive. A plate current accordingly now flows through the resistor R8 which thereby lowers the voltage on the plate and causing a current to then flow through the resistor R7 and the crystal diode CR3 to the plate of section V2B due to the lower voltage thereon. The flow of current thus ensuing through resistor R7 and diode CR3 causes a voltage drop across resistor R7 which lowers the voltage on the grid of "OR" gate tube section V2A even though the plate of "ON" tube section V1B is still at a high potential and such section is then non-conducting. This voltage decrease on the grid of section V2A reduces the current flowing through resistor R22, which is further lowered by the constant voltage drop through resistor R21, resulting in a drop in the voltage on the grid of current regulator and feedback amplifier tube V4 below its cut-off thereby terminating current flow through the filament of lamp 14.

It is thus seen that the "OR" gate 9 comprising the cathode follower tube section V2A operates to cause transmission of a pulse through the lamp 14 only when section V1B of the "ON" square wave generator and section V2B of the "OR" gate are both non-conducting. Also the "gate" comprising the resistor R7 and crystal diodes CR2 and CR3 remains closed as long as "OFF" tube section V3A is non-conducting but as capacitor C17 recharges through potentiometer R12 the potential on the grid of section V3A rises thereby rendering such tube section again conductive. The resulting flow of current through load resistor R10 and "OFF" tube section V3A causes a voltage drop across load resistor R10 which is coupled by capacitor C2 and resistor R9 to the grid of "OR" tube section V2B, so that such voltage drop on the grid returns tube section V2B to its normal non-conducting state.

It is also to be noted that the time constants of the capacitor C17 and the setting of potentiometer R12 is such that the "OFF" square wave generator comprising the multivibrator tube V3 will remain in the condition of section V3A non-conducting and section V3B conducting, until after the "ON" generator 7 comprising the multivibrator tube V1 has returned to its normal state with section V1B conducting. This operation is to prevent any

possibility of a double pulse because if "OFF" tube section V3A returned to its normal conducting state while "ON" tube section V1B was still non-conducting a narrowed second pulse could otherwise occur for the unexpired duration of the normal "ON" pulse. Hence "OFF" section V3B is timed to remain in a conducting state thereby causing "OR" section V2B to conduct until "ON" section V1B has returned to its normal conducting condition. This allows tube sections V3B and V2B to safely return to their respective normal non-conducting conditions because the plate of "ON" tube section V1B is no longer at a high potential ready for a pulse and the entire circuit is again at its "pre-pulse" condition as previously described awaiting another pulse from the trigger pulse generator 5.

Should the pulse fail to cause the voltage across the lamp 14 to rise to 300 volts, or whatever such voltage has been preset by potentiometer R36, the circuit remains as previously described with repetition of the pulse until the preset voltage for the lamp 14 is reached, since the "gate" consisting of resistor R7 and crystal diodes CR2 and CR3 is closed off until resumption of "ON" section V1B conduction by recharging of capacitor C1 through resistor R4. In the event any subsequent pulse should cause the voltage across the lamp 14 to exceed the set cut-off voltage of 300 volts, then "Voltage Comparator" tube section V7B will again become non-conducting causing "OFF" section V3B to become conducting along with that of "OR" tube section V2B thereby stopping current flow through the "gate," comprising the previously mentioned crystal diode CR3 and resistor R7, and terminating the pulse. A variation in the duration of the "ON" pulse within certain limits is obtained by adjustment of the potentiometer R16 while the length of time in which the "OFF" multivibrator tube section V3B is conducting can be controlled by selecting the voltage supplied to its grid through adjustment of potentiometer R17. After the lamp 14 has been thus getter flashed, the machine indexes such flashed lamp out of the getter flashing station and a new lamp is indexed into such station with the trigger pulse from the generator 5 being again interrupted by closing of the previously mentioned cam-operated switch 24.

After "getter flashing" in accordance with the present invention, the lamp 14 may be further processed, if desired, by applying a color filter coating over the envelope portion thereof. Since the filament is completely unrecrystallized and is "tough," the lamp 14 may be machine packed or sold loose from bins or store counters without fear of breakage due to brittle filaments. When the lamp is first operated by the user, the filament will recrystallize.

As a specific example for processing a miniature lamp in accordance with the present invention, 0.02 milligram of red phosphorus getter is placed onto the filament of a 7 watt C-7½ multiple-type Christmas lamp before the mount is sealed to the lamp envelope. After the lamp is evacuated, sealed, and the base affixed to the envelope neck, the getter is flashed from the filament in accordance with the present invention.

The lamp 14, as shown in FIG. 2, is generally standard in that it comprises an envelope 30, conventional filament-supporting stem mount 32 sealed to the envelope neck, and lead-in wires 34 sealed through the stem and supporting the filament 36. The lead-in wires 34 connect to the lamp base 38. An additional support wire 40 supports the filament 36 at its mid-point. The finished lamp is unusual in that the filament is completely unrecrystallized and is completely free from any adhering getter material, and yet the lamp envelope also encloses the reaction products of getter material flashed from direct contact with the filament by self-resistance heating of same. These reaction products of getter material will comprise phosphorus-containing compound, in the case of the specific red phosphorus material considered hereinbefore, although other getter materials may be substituted for the red phosphorus

example considered hereinbefore. Other materials such as aluminum oxide may also be flashed from the filament along with the phosphorus, and the use of a supplemental aluminum oxide "filament flashed" material is known.

In the case of miniature-type lamps, it is preferred that the filament be completely unrecrystallized, as is readily determined by examining its microstructure. It should be understood, however, that in some cases, it may be desirable to flash the filament so that some incipient filament recrystallization takes place. The present method and apparatus can also be used to getter flash a lamp in this manner simply by raising the getter flashing temperature a small amount.

It should be understood that the specific flashing apparatus as described hereinbefore is subject to considerable modification. The method could also be practiced by hand by modifying the constant current pulses so that heating of the filament occurs at a slower rate. The IR drop developed across the filament, as it is heated up, could then be monitored and the generator manually adjusted to vary the duration of the output of the pulse constant current pulses to maintain the filament at its flashing temperature.

It should thus be apparent to those skilled in the art from the foregoing that an electronic flashing control system for gettering electric lamps has been herein provided in which a constant current is supplied to the lamp during flashing of the getter. Moreover, the system provides for a very rapid rise in the voltage across the lamp until a preselected temperature maximum is reached after which such temperature is held substantially at such preselected value to thus maintain the filament of the lamp at a constant temperature during getter flashing to prevent recrystallization of such filament. By such accurate control of current, temperature and voltage, the time required to getter flash the lamp is substantially reduced from that heretofore required thereby producing a higher quality lamp at reduced manufacturing cost.

Although one embodiment of the present invention has been herein shown and described it is to be understood that still further modifications thereof may be made without departing from the spirit and scope of the invention.

I claim as my invention:

1. An electronic flashing control system for rapidly getter flashing electric lamps without recrystallization of the filament thereof comprising:

- (a) means operable to apply constant current pulses through the filament of the electric lamp being getter flashed to produce a predetermined voltage drop across said lamp,
- (b) means operable to maintain said predetermined voltage drop across said lamp constant for a preselected period of time to cause the temperature of said filament to remain at a substantially uniform desired value during getter flashing of said lamp to prevent recrystallization of said lamp filament, and
- (c) means operable after the lapse of a definite period of time to render said system ineffective during transfer of a flashed lamp out of its getter flashing position and a new lamp into such position.

2. An electronic flashing control system for rapidly getter flashing electric lamps without recrystallization of the filament thereof comprising:

- (a) means operable to apply constant current pulses of preselected frequency and duration through the filament of the electric lamp being getter flashed to heat said filament and rapidly produce a voltage drop of predetermined magnitude across said lamp,
- (b) means operable to maintain said voltage drop of predetermined magnitude across said lamp constant for a preselected period of time to cause the temperature of said filament to remain at a substantially uniform desired value during such preselected period of time to prevent recrystallization of said lamp filament, and

(c) means operable after the lapse of such preselected period of time to render said system ineffective during transfer of a flashed lamp out of its getter flashing position and a new lamp into such position.

3. An electronic flashing control system for rapidly getter flashing electric lamps without recrystallization of the filament thereof comprising:

- (a) a source of supply including a current regulator and feedback amplifier tube for heating the filament of the electric lamp being getter flashed,
- (b) control means connected to said current regulator and feedback amplifier tube and operable to cause said source to supply constant current pulses of preselected frequency and duration to said filament to rapidly produce a voltage drop of predetermined magnitude across said lamp,

(c) comparator and cut-off means connected to said source of supply and to said control means and operable to cause said control means to maintain the magnitude of the voltage drop across said lamp constant with production of a constant preselected temperature of said filament to prevent recrystallization of the latter during gettering of said lamp, and

(d) means operable after the lapse of a predetermined period of time to render said system ineffective during transfer of a flashed lamp out of its getter flashing position and a new lamp into such position.

4. An electronic flashing control system for rapidly getter flashing electric lamps without recrystallization of the filament thereof comprising:

- (a) a source of supply including a controlling amplifier tube and operable to heat the filament of the electric lamp being getter flashed to a predetermined temperature,

(b) a control circuit connected to said controlling amplifier tube to operate the latter and cause said source to supply constant current pulses of preselected frequency and duration to the filament of said lamp being getter flashed to rapidly produce a voltage drop across said lamp of predetermined magnitude,

(c) a comparator and cut-off circuit connected to said source of supply and to said control circuit and operable to cause said control circuit to maintain said controlling amplifier tube operative and hence the voltage drop of predetermined magnitude at a constant value to produce a constant preselected temperature of said filament and prevent recrystallization of the latter during getter flashing of said lamp, and

(d) switch means operable after the lapse of a predetermined period of time during which said filament temperature has been maintained constant to then render said system ineffective during transfer of a flashed lamp out of its getter flashing position and a new lamp into such position.

5. An electronic flashing control system for rapidly getter flashing electric lamps without recrystallization of the filament thereof comprising:

- (a) a circuit for energizing the lamp to be getter flashed including a current regulator and feedback amplifier tube and operable to cause energization of said lamp from a high voltage source of supply,
- (b) a high frequency trigger pulse generator for triggering a train of pulses at a predetermined frequency during gettering of said lamp,
- (c) an "ON" square wave generator including a multivibrator tube operable by the pulses from said trigger pulse generator to emit a square wave signal pulse of predetermined length,
- (d) a control gate circuit including a cathode follower tube and operable by the signal pulse of predetermined length from said square wave generator to cause a constant voltage pulse to be impressed

upon said current regulator and feedback amplifier tube to render it operable to cause energization of said lamp with a constant current pulse of the same duration as that of said square wave pulse; and

(e) a voltage comparator and cut-off circuit, including the current regulator and feedback amplifier tube of said lamp energizing circuit and a triode tube, and operable in response to the voltage across said lamp reaching a preselected value to cause current flow through said triode tube with attendant operation of said control gate circuit causing de-energization of said lamp.

6. An electronic flashing control system for rapidly getter flashing electric lamps without recrystallization of the filament thereof comprising:

- (a) a circuit for energizing the lamp to be getter flashed including a current regulator and feedback amplifier tube and operable to cause energization of said lamp,
- (b) a high frequency trigger pulse generator for triggering a train of pulses at a predetermined frequency during gettering of said lamp,
- (c) an "ON" square wave generator including a multivibrator tube operable by the pulses from said trigger pulse generator to emit a square wave signal pulse of predetermined length,
- (d) a control gate circuit including a cathode follower tube and operable by the signal pulse of predetermined length from said square wave generator to cause a constant voltage pulse to be impressed upon said current regulator and feedback amplifier tube to render it operable to cause energization of said lamp with a constant current pulse of the same duration as that of said square wave pulse;
- (e) a voltage comparator and cut-off circuit, including the current regulator and feedback amplifier tube of said lamp energizing circuit and a dual triode tube, and operable in response to the voltage across said lamp reaching a preselected value to cause current flow through said dual triode tube;
- (f) and an "OFF" square wave generator including a multivibrator tube connected to said control gate circuit and to said voltage comparator and cut-off circuit and operable in response to current flow through said latter circuit to cause said control gate circuit to render said current regulator and feedback amplifier tube non-conductive with deenergization of said lamp whenever the voltage developed by the constant current pulse across said lamp exceeds its preset value whereby current flow through said lamp and the temperature of its filament is maintained constant for a preselected time period to expedite getter flashing of said lamp and preclude recrystallization of its filament.

7. An electronic flashing control system for rapidly getter flashing electric lamps without recrystallization of the filament thereof comprising:

- (a) a circuit for energizing the lamp to be getter flashed including a current regulator and feedback amplifier tube and operable to cause energization of said lamp from a high voltage source of supply,
- (b) a high frequency trigger pulse generator for triggering a train of pulses at a predetermined frequency of approximately 500 pulses per second and for a duration of about 1.6 seconds during gettering of said lamp,
- (c) an "ON" square wave generator including a multivibrator tube operable by the pulses from said trigger pulse generator to emit a square wave signal pulse of predetermined length,
- (d) a control gate circuit including a cathode follower tube and operable by the signal pulse of predetermined length from said square wave generator to cause a constant voltage pulse to be impressed upon said current regulator and feedback amplifier tube

to render it operable to cause energization of said lamp with a constant current pulse of the same duration as that of said square wave pulse;

- (e) a voltage comparator and cut-off circuit, including the current regulator and feedback amplifier tube of said lamp energizing circuit and a dual triode tube, and operable in response to the voltage across said lamp reaching a preselected value to cause current flow through said dual triode tube;
- (f) and an "OFF" square wave generator including a multi-vibrator tube connected to said control gate circuit and to said voltage comparator and cut-off circuit and operable in response to current flow through said latter circuit to cause said control gate circuit to render said current regulator and feedback amplifier tube non-conductive with deenergization of said lamp whenever the voltage developed by the constant current pulse across said lamp exceeds its preset value whereby current flow through said lamp and the temperature of its filament is maintained constant for a preselected time period to expedite getter flashing of said lamp and preclude recrystallization of its filament.

8. An electronic flashing control system for rapidly getter flashing electric lamps without recrystallization of the filament thereof comprising:

- (a) a circuit for energizing the lamp to be getter flashed including a current regulator and feedback amplifier tube and operable to cause energization of said lamp,
- (b) a high frequency trigger pulse generator for triggering a train of pulses at a predetermined frequency during gettering of said lamp,
- (c) an "ON" square wave generator including a multivibrator tube operable by the pulses from said trigger pulse generator to emit a square wave signal pulse of predetermined length,
- (d) a control gate circuit including a cathode follower tube and a constant current regulator tube and operable by the signal pulse of predetermined length from said square wave generator to cause a constant voltage pulse to be impressed by said control gate circuit upon the current regulator and feedback amplifier tube of said lamp energizing circuit to render such tube operable to cause energization of said lamp with a constant current pulse of the same duration as that of said square wave pulse;
- (e) a voltage comparator and cut-off circuit, including the current regulator and feedback amplifier tube of said lamp energizing circuit and a dual triode tube, and operable in response to the voltage across said lamp reaching a preselected value to cause current flow through said dual triode tube;
- (f) and an "OFF" square wave generator including a multivibrator tube connected to said control gate circuit and to said voltage comparator and cut-off circuit and operable in response to current flow through said latter circuit to cause said control gate circuit to render said current regulator and feedback amplifier tube non-conductive with deenergization of said lamp until after cessation of the square wave signal pulse of predetermined length than being supplied to said control gate circuit by said "ON" square wave generator, whereby current flow through said lamp and the temperature of its filament is maintained constant for a preselected time period to expedite getter flashing of said lamp and preclude recrystallization of its filament.

9. An electronic flashing control system for rapidly getter flashing electric lamps without recrystallization of the filament thereof comprising:

- (a) a circuit for energizing the lamp to be getter flashed including a current regulator and feedback amplifier tube and operable to cause energization of said lamp,
- (b) a high frequency trigger pulse generator for trig-

- gering a train of pulses at a predetermined frequency during gettering of said lamp,
- (c) an "ON" square wave generator including a multivibrator tube having one side connected to a supply source and normally conductive while its other side is non-conductive until pulses from said trigger pulse generator are impressed thereon to cause a reversal in the conductivity of both sides of said multivibrator tube with attendant production of a square wave signal pulse of predetermined length, 5
- (d) a control gate circuit including a cathode follower tube and a constant current regulator tube and operable by the signal pulse of predetermined length from said square wave generator to cause a constant voltage pulse to be impressed by said control gate circuit upon the current regulator and feedback amplifier tube of said lamp energizing circuit to render such tube operable to cause energization of said lamp with a constant current pulse of the same duration as that of said square wave pulse; 10
- (e) a voltage comparator and cut-off circuit including the current regulator and feedback amplifier tube of said lamp energizing circuit and a dual triode tube, and operable in response to the voltage across said lamp reaching a preselected value to cause current flow through said dual triode tube; 15
- (f) and an "OFF" square wave generator including a multivibrator tube connected to said control gate circuit and to said voltage comparator and cut-off circuit and operable in response to current flow through said latter circuit to cause said control gate circuit to render said current regulator and feedback amplifier tube non-conductive with deenergization of said lamp whenever the voltage developed by the constant current pulse across said lamp exceeds its preset value and with such deenergization lasting until after cessation of the square wave signal pulse of predetermined length then being supplied to said control gate circuit by said "ON" square wave generator, whereby current flow through said lamp and the temperature of its filament is maintained constant for a preselected time period to expedite getter flashing of said lamp and preclude recrystallization of its filament. 20
10. An electronic flashing control system for rapidly getter flashing electric lamps without recrystallization of the filament thereof comprising: 25
- (a) a circuit for energizing the lamp to be getter flashed including a current regulator and feedback amplifier tube and operable to cause energization of said lamp,
- (b) a high frequency trigger pulse generator for triggering a train of pulses at a predetermined frequency during gettering of said lamp, 30
- (c) an "ON" square wave generator including a multivibrator tube having one side connected to a supply source and normally conductive while its other side is non-conductive until pulses are impressed thereon from said trigger pulse generator to cause a reversal in the conductivity of both sides of said multivibrator tube with attendant production of a square wave signal pulse of predetermined length, 35
- (d) a control gate circuit including a constant current regulator tube and a cathode follower tube, said cathode follower tube having one side thereof conductively operable to normally pass a small current to maintain its cathode just a few volts above its grid potential, and having its other side operable with a heavier current flow upon the application of a square wave signal pulse of predetermined length from said square wave generator to cause a constant voltage pulse to be impressed by said control gate circuit upon the current regulator and feedback amplifier tube of said lamp energizing circuit to render such tube operable to cause energization of said lamp with a constant current pulse of the same duration as that of said square wave pulse; 40
- (e) a voltage comparator and cut-off circuit, including the current regulator and feedback amplifier tube of said lamp energizing circuit and a dual triode tube, and operable in response to the voltage across said lamp reaching a preselected value to cause said dual triode tube to generate a positive pulse; 45
- (f) and an "OFF" square wave generator including a multivibrator tube connected to said control gate circuit and to said voltage comparator and cut-off circuit and operable in response to the current pulse through said latter circuit to cause said control gate circuit to render said current regulator and feedback amplifier tube non-conductive with deenergization of said lamp until after cessation of the square wave signal pulse of predetermined length then being supplied to said control gate circuit by said "ON" square wave generator, whereby current flow through said lamp and temperature of its filament is maintained constant for a preselected time period to expedite getter flashing of said lamp and preclude recrystallization of its filament. 50
- (e) a voltage comparator and cut-off circuit, including 55
- (d) a control gate circuit including a constant current regulator tube and a cathode follower tube, said cathode follower tube having one side thereof conductively operable to normally pass a small current to maintain its cathode just a few volts above its grid potential, and having its other side operable with a heavier current flow upon the application of a square wave signal pulse of predetermined length from said square wave generator to cause a constant voltage pulse to be impressed by said control gate circuit upon the current regulator and feedback amplifier tube of said lamp energizing circuit to render such tube operable to cause energization of said lamp with a constant current pulse of the same duration as that of said square wave pulse; 60
- (e) a voltage comparator and cut-off circuit, including the current regulator and feedback amplifier tube of said lamp energizing circuit and a dual triode tube, and operable in response to the voltage across said lamp reaching a preselected value to cause said dual triode tube to generate a positive pulse; 65
- (f) and an "OFF" square wave generator including a multivibrator tube connected to said control gate circuit and to said voltage comparator and cut-off circuit and operable in response to the current pulse through said latter circuit to cause said control gate circuit to render said current regulator and feedback amplifier tube non-conductive with deenergization of said lamp until after cessation of the square wave signal pulse of predetermined length then being supplied to said control gate circuit by said "ON" square wave generator, whereby current flow through said lamp and temperature of its filament is maintained constant for a preselected time period to expedite getter flashing of said lamp and preclude recrystallization of its filament. 70
- (e) a voltage comparator and cut-off circuit, including 75

- the current regulator and feedback amplifier tube of said lamp energizing circuit and a dual triode tube, and operable in response to the voltage across said lamp reaching a preselected value to cause current flow through said dual triode tube;
- (f) and an "OFF" square wave generator including a multivibrator tube connected to said control gate circuit and to said voltage comparator and cut-off circuit and operable in response to current flow through said latter circuit to cause said control gate circuit to render said current regulator and feedback amplifier tube non-conductive with deenergization of said lamp whenever the voltage developed by the constant current pulse across said lamp exceeds its preset value and with such deenergization lasting until after cessation of the square wave signal pulse of predetermined length then being supplied to said control gate circuit by said "ON" square wave generator, whereby current flow through said lamp and the temperature of its filament is maintained constant for a preselected time period to expedite getter flashing of said lamp and preclude recrystallization of its filament.
11. An electronic flashing control system for rapidly getter flashing electric lamps without recrystallization of the filament thereof comprising:
- (a) a circuit for energizing the lamp to be getter flashed including a current regulator and feedback amplifier tube and operable to cause energization of said lamp,
- (b) a high frequency trigger pulse generator for triggering a train of pulses at a predetermined frequency during gettering of said lamp,
- (c) an "ON" square wave generator including a multivibrator tube having one side connected to a supply source and normally conductive while its other side is non-conductive until pulses are impressed thereon from said trigger pulse generator to cause a reversal in the conductivity of both sides of said multivibrator tube with attendant production of a square wave signal pulse of predetermined length,
- (d) a control gate circuit including a constant current regulator tube and a cathode follower tube, said cathode follower tube having one side thereof conductively operable to normally pass a small current to maintain its cathode just a few volts above its grid potential, and having its other side operable with a heavier current flow upon the application of a square wave signal pulse of predetermined length from said square wave generator to cause a constant voltage pulse to be impressed by said control gate circuit upon the current regulator and feedback amplifier tube of said lamp energizing circuit to render such tube operable to cause energization of said lamp with a constant current pulse of the same duration as that of said square wave pulse;
- (e) a voltage comparator and cut-off circuit, including the current regulator and feedback amplifier tube of said lamp energizing circuit and a dual triode tube, and operable in response to the voltage across said lamp reaching a preselected value to cause said dual triode tube to generate a positive pulse;
- (f) and an "OFF" square wave generator including a multivibrator tube connected to said control gate circuit and to said voltage comparator and cut-off circuit and operable in response to the current pulse through said latter circuit to cause said control gate circuit to render said current regulator and feedback amplifier tube non-conductive with deenergization of said lamp until after cessation of the square wave signal pulse of predetermined length then being supplied to said control gate circuit by said "ON" square wave generator, whereby current flow through said lamp and temperature of its filament is maintained constant for a preselected time period to expedite getter flashing of said lamp and preclude recrystallization of its filament.

12. An electronic flashing control system for rapidly getter flashing electric lamps without recrystallization of the filament thereof comprising:
- a circuit for energizing the lamp to be getter flashed including a current regulator and feedback amplifier tube and operable to cause energization of said lamp from a high voltage source of supply, 5
  - a high frequency trigger pulse generator for triggering a train of pulses at a predetermined frequency during gettering of said lamp,
  - an "ON" square wave generator including a multivibrator tube having one side connected to a supply source and normally conductive while its other side is non-conductive until pulses are impressed thereon from said trigger pulse generator to cause a reversal in the conductivity of both sides of said multivibrator tube with attendant production of a square wave signal pulse of predetermined length, 15
  - a control gate circuit including a constant current regulator tube and a cathode follower tube, said cathode follower tube having one side thereof conductively operable to normally pass a small current to maintain its cathode just a few volts above its grid potential, and having its other side operable with a heavier current flow upon the application of a square wave signal pulse of predetermined length from said square wave generator to cause a constant voltage pulse to be impressed by said control gate circuit upon the current regulator and feedback amplifier tube of said lamp energizing circuit to render such tube operable to cause energization of said lamp with a constant current pulse of the same duration as that of said square wave pulse; 20
  - a voltage comparator and cut-off circuit, including the current regulator and feedback amplifier tube of said lamp energizing circuit and a dual triode tube having both sides thereof normally conductive, said voltage comparator and cut-off circuit being operable, in response to the voltage across said lamp reaching a preselected value and rendering one side of said dual triode tube non-conductive, to generate a positive pulse; 30
  - and an "OFF" square wave generator including a multivibrator tube connected to said control gate circuit and to said voltage comparator and cut-off circuit and operable in response to the current pulse through said latter circuit to cause said control gate circuit to render said current regulator and feedback amplifier tube non-conductive with deenergization of said lamp whenever the voltage developed by the constant current pulse across said lamp exceeds its preset value and with such deenergization lasting until after cessation of the square wave signal pulse of predetermined length then being supplied to said control gate circuit by said "ON" square wave generator, whereby current flow through said lamp and the temperature of its filament is maintained constant for a preselected time period to expedite getter flashing of said lamp and preclude recrystallization of its filament. 40
13. The method of rapidly getter flashing the filament of an electric lamp without recrystallization of the filament thereof comprising:
- subjecting the filament of such lamp to constant current electrical pulses of preselected frequency and duration to rapidly produce a voltage drop of predetermined magnitude across said lamp, 45
  - controlling the time of application of the constant current pulses to the filament to produce a constant voltage drop of preselected magnitude across the lamp as a measure of a preselected ensuing temperature of the filament to prevent recrystallization thereof during flashing of the lamp, and 70
  - interrupting the application of the constant current pulses of preselected frequency and duration to the 75

- lamp filament after the lapse of the preselected period of time and during transfer of a flashed lamp out of its getter flashing position and a new lamp into such position.
14. The method of rapidly getter flashing the filament of an electric lamp without recrystallization of the filament thereof comprising:
- applying constant current electrical pulses of preselected frequency and duration to the filament of the lamp for a period of time sufficient to rapidly produce a voltage drop of predetermined magnitude across said lamp,
  - decreasing the period of time during which each constant current pulse is applied to the filament once the voltage drop across said lamp has reached the predetermined magnitude to thus maintain such voltage drop constant and as a measure of an ensuing constant filament temperature, and
  - discontinuing the application of the constant current pulses to the lamp filament after the lapse of a preselected period of time during which such filament has been maintained at a constant temperature to prevent recrystallization thereof during flashing of the lamp. 25
15. Apparatus for heating an unrecrystallized filament, which displays an electrical resistance which increases sharply with temperature, in order to flash a getter material from said filament without causing the filament to recrystallize, which apparatus comprises:
- current supply means for passing through said filament a series of constant current pulses of preselected duration and magnitude to rapidly heat said filament to a predetermined temperature sufficient to flash said getter material from said filament but insufficient to cause said filament to recrystallize;
  - voltage detecting and signalling means responsive to the IR drop developed across said filament when the constant current pulses are passed therethrough, and said voltage detecting and signalling means generating a control signal when the IR drop developed across said filament reaches a predetermined value signifying that said predetermined filament getter flashing temperature has been achieved;
  - current pulse control means responsive to the control signal generated by said voltage detecting and signalling means to shorten the duration of each constant current pulse passed through said filament by said current supply means to decrease the average wattage consumed by said filament by such amount that the resulting IR drop across said filament during each such shortened constant current pulse applied therethrough is maintained substantially at that predetermined value which indicates that the predetermined filament getter flashing temperature has been achieved; and
  - timing means for controlling said current supply means to pass constant current pulses through said filament for a predetermined time sufficient to completely flash the getter material from said filament. 40
16. The method of heating an unrecrystallized filament, which displays an electrical resistance which increases sharply with temperature, in order to flash a getter material without causing the filament to recrystallize, which method comprises:
- initially applying across said filament a series of constant current pulses of predetermined magnitude and duration;
  - detecting the voltage developed across said filament during the applied constant current pulses;
  - when the detected voltage reaches a predetermined value signifying that the filament has achieved a predetermined temperature sufficient to flash said getter, but insufficient to recrystallize said filament, modifying the applied constant current pulse so that the 55

average voltage consumed by said filament is just sufficient to maintain said filament at about said predetermined getter flashing temperature; and

(d) continuing to apply across said heated filament such modified constant current pulses to maintain said filament at the predetermined temperature required to flash said getter for a sufficient time to completely flash said getter. 5

17. The method of heating an unrecrystallized filament, which displays an electrical resistance which increases sharply with temperature, in order to flash a getter material without causing the filament to recrystallize, which method comprises: 10

- (a) initially applying across the filament a series of current pulses of predetermined magnitude and duration with a predetermined interval between each pulse to rapidly heat said filament; 15
- (b) detecting the voltage developed across the filament when the constant current pulses are passed therethrough;
- (c) when the detected voltage reaches a predetermined value signifying that the filament has achieved a 20

predetermined temperature sufficient to flash said getter, but insufficient to recrystallize said filament, decreasing the duration of each applied constant current pulse by a predetermined amount sufficient to maintain said filament at about said predetermined getter flashing temperature; and

(d) continuing to apply across said heated filament such constant current pulses of predetermined shortened duration to maintain said filament for a predetermined time at the predetermined temperature required to flash said getter.
